US0D1053353S

(12) **United States Design Patent** (10) Patent No.: **US D1,053,353 S**
(45) Date of Patent: ** Dec. 3, 2024

(54) **ORTHOPEDIC SCREW**(71) Applicant: **RESTOR3D, INC.**, Durham, NC (US)(72) Inventors: **Sarah Starego**, Durham, NC (US);
Alexandra Falis, Durham, NC (US)(73) Assignee: **Restor3D, Inc.**, Durham, NC (US)(***) Term: **15 Years**(21) Appl. No.: **29/873,094**(22) Filed: **Mar. 24, 2023**(51) LOC (14) Cl. **24-03**

(52) U.S. Cl.

USPC ..... **D24/155**(58) **Field of Classification Search**USPC D24/155-157; D8/387, 391-392
CPC . A61B 17/864; A61B 17/863; A61B 17/8635;
A61B 17/8685

(57) **CLAIM**

The ornamental design for an orthopedic screw as shown and described.

DESCRIPTION

FIG. 1 is a perspective view of an orthopedic screw;
FIG. 2 is another perspective view of the orthopedic screw;
FIG. 3 is a side view of the orthopedic screw;
FIG. 4 is another side view of the orthopedic screw;
FIG. 5 is a back view of the orthopedic screw;
FIG. 6 is another side view of the orthopedic screw;
FIG. 7 is another side view of the orthopedic screw; and,
FIG. 8 is a front view of the orthopedic screw.
The broken lines form no part of the claimed design and illustrate portions of the orthopedic screw.

1 Claim, 3 Drawing Sheets
